DESIGN FOR A RING

Ernest O. Crocker, Washington, D. C.

Application April 9, 1943, Serial No. 109,943

Term of patent 3½ years

To all whom it may concern:

Be it known that I, Ernest O. Crocker, a citizen of the United States residing at 813 Randolph Street, N. W., Washington, D. C., have invented a new, original, and ornamental Design for a Ring, of which the following is a specification, reference being had to the accompanying drawing, forming part thereof.

Fig. 1 is a top plan view of a ring, showing my new design.

Fig. 2 is an end elevational view, and
Fig. 3 is a side elevational view thereof.

I claim:

The ornamental design for a ring, as shown.

ERNEST O. CROCKER.
